UNITED STATES PATENT OFFICE.

JAMES A. CHARTER, OF CHICAGO, ILLINOIS.

COMBUSTION-ENGINE.

1,081,017.

Specification of Letters Patent. Patented Dec. 9, 1913.

Application filed August 7, 1912. Serial No. 713,766.

To all whom it may concern:

Be it known that I, JAMES A. CHARTER, a citizen of the United States, residing at Chicago, in the county of Cook and State of Illinois, have invented a certain new and useful Improvement in Combustion-Engines, of which the following is a specification.

This invention relates to that class of explosive engines in which a rotating sleeve 10 or cylindrical valve is used.

The object of the invention is to provide a device of this class which is especially simple, and accessible, and inexpensive to build; which is efficient in operation and not 15 readily liable to get out of order.

The invention consists in providing the piston of the engine with a stationary cylinder in which the piston travels, thereby doing away with unnecessary friction and 20 strain upon the piston; in using said stationary cylinder as a protection for the cylindrical valve member from the fire of the engine and the wear of the piston and in driving the valve member by a portion of it 25 which is closely adjacent to the drive shaft of the engine, thereby reducing the size and number of driving parts necessary to propel it.

The invention further consists in other 30 features taken alone and in combination with the above which will be more fully set forth in the specification and claims.

Figures 1 and 2 are central sectional detail views through cylinder constructions 35 illustrating my invention, Fig. 1 being the preferred form and Fig. 2 a modification thereof.

It is to be understood that the device here 40 illustrated, is intended for use in a complete engine of the type referred to, ordinarily of two or more cylinders, having crank shafts, piston rods, piping, spark plugs, a carbureter, and so forth, as is usually required in a complete engine of this type. 45 If more detailed description is required, reference is made to my companion application filed herewith, Serial No. 713,765.

In the drawings similar numerals refer to the same parts throughout the several views.

50 The device is, of course, supported upon some sort of a base frame or casing, the top of which 10 appears in the figures. Rigidly secured to this base 10 by bolts 12 is a casting forming an outer cylinder 14, having between its two walls a water space 16 within 55 which water may be circulated in any suit-

able manner, as is usual for cooling the engine. In other words, this cylinder is, what is commonly called, a water jacket. The upper end of this outer or water jacket cylinder 14 is closed by a hollow plate 18 secured in position by suitable bolts 20. In the form shown in Fig. 1, this plate 18 has integral with it a cylinder 60 of less diameter than the water jacket cylinder 14. This cylinder 60 extends entirely through the water jacket cylinder, leaving between the two cylinders an annular space within which a cylindrical valve 24 fits and rotates. As shown, this cylindrical valve extends appreciably below the jacket cylinder 14 into a receptacle 26, formed in any suitable manner of any suitable size. In the particular case here illustrated, this receptacle 26 is a space formed between the base frame 10 and the bottom portions of the cylinders. The lower end of this cylindrical valve member 24 is preferably supported by ball bearings 28 working upon hardened surfaces 30 above and below them in the usual manner.

Made with or otherwise mounted upon the lower portion of the cylindrical valve 24 is a gear 34. In the particular case here illustrated, it is a worm gear driven by a worm 36, but any other form of gearing may be used without departing from this invention. This worm 36 is driven by means well known in the art and not here shown, ordinarily connecting it to the main crank shaft of the engine, also not shown, which is in turn, in the ordinary manner, rotated by the piston rod on the piston (not shown) which normally reciprocates inside the cylinder 60.

In the upper portion of the cylinder 60 and ordinarily above the path of travel of the piston (not shown) are a plurality of ports 42 and 44 for the ingress and egress of gas. These ports extend through the walls of the water jacket 14 as well as through the inner cylinder 60. The cylindrical valve member 24 is provided with one or more ports (not appearing in the figures) adapted to register with the ports 42 and 44. In other words the device is provided with suitable ports, well known in the art to render it operative.

The valve 24 may be balanced by any suitable method, one of which is shown and described in my above prior application without in any way departing from this invention.

It will be noticed that by the use of the

foregoing construction the cylindrical valve 24 is protected from the wear of the piston which travels in the inner cylinder 60, while at the same time it is kept cool by the water jacket 14 and that it is driven from its lower end in close proximity to the crank shaft of the engine, much simpler mechanism being therefore required than were this cylindrical valve driven from the top 10 of the engine as is shown in my above mentioned application, while as shown in Fig. 1 the inner cylinder extends sufficiently below the water jacket to bear upon the base support 10 in any suitable sort of joint 62, thereby steadyng this end of the cylinder 15 against any motion of the piston. It will also be noticed that by removing the bolts 20 the entire inner cylinder may be removed for repairs and replacement without disturbing the other parts.

In Fig. 2 is shown a modified form of structure with a reduced size combustion chamber 64 carrying its own closed end 66, all as more fully shown, described, and 25 claimed in the above mentioned prior application. In this case the cylinder 68 also rests upon the base 10 in a joint 70.

Having thus described my invention what I claim as new and desire to secure by Letters Patent is—

1. In a device of the class described, in combination with a base, a cylinder secured to said base, a second cylinder inside the first cylinder, spaced apart from it to form 35 an annular recess between the two cylinders, a valve in said recess, means connecting the end of the inner cylinder to the base member, means connecting the opposite end of said cylinder to the outer cylinder, and 40 means located within a space formed between a portion of the end of the outer cylinder, a portion of the end of the inner cylinder and the base member for driving said valve.
- 45 2. In a device of the class described, in combination with a base member, an outer cylinder secured to and rising from the base member, an inner cylinder smaller than the outer cylinder adapted to be inserted through the outer cylinder into 50

engagement with a guiding support on the base, a flanged head on the upper end of the inner cylinder fitting over the upper end of the outer cylinder, means securing said flanged head to the outer cylinder, and a 55 rotatable cylindrical valve member in an annular space formed between said two cylinders.

3. In a device of the class described, in combination with a base member, an outer cylinder secured to and rising from the base member, an inner cylinder smaller and longer than the outer cylinder adapted to be inserted through the outer cylinder into engagement with a guiding projection on the base, a flanged head on the upper end of the inner cylinder fitting over the upper end of the outer cylinder, means securing said flanged head to the outer cylinder, a 60 rotatable cylindrical valve in the annular 65 space formed between said two cylinders adapted to control ports for the admission and exhaust of gas to the inner cylinder, and means for rotating said valve member.

4. In a device of the class described, in combination with a base member, an outer cylinder secured to and rising from the base member, an inner cylinder smaller and longer than the outer cylinder adapted to be inserted through the outer cylinder into 70 engagement with a guiding projection on the base, a flanged head on the upper end of the inner cylinder fitting over the end of the outer cylinder, means securing said flanged head to the outer cylinder, a rotatable cylindrical valve member in the annular 75 space formed between said two cylinders adapted to control entrance and exhaust ports leading into the inner cylinder and means located immediately adjacent to 80 the base and adjacent to the lower end of the inner cylinder for rotating said valve member.

In witness whereof I have hereunto subscribed my name in the presence of two 85 witnesses.

JAMES A. CHARTER.
